UNITED STATES PATENT OFFICE.

DAVID PLATTNER AND RODNEY H. YALE, OF LINCOLN, NEBRASKA, ASSIGNEES TO
PLATTNER-YALE MANUFACTURING COMPANY, OF LINCOLN, NEBRASKA, A COR-
PORATION OF NEBRASKA.

BOB-SLED RUNNER.

1,222,322.

Specification of Letters Patent. Patented Apr. 10, 1917.

Application filed September 2, 1916. Serial No. 118,237.

To all whom it may concern:

Be it known that we, DAVID PLATTNER and RODNEY H. YALE, citizens of the United States, and residents of Lincoln, county of 5 Lancaster, and State of Nebraska, have invented certain new and useful Improvements in Bob-Sled Runners, of which the following is a specification.

This invention relates to certain improvements in bob sled runners, and the like; and the objects and nature of the invention will be readily understood by those skilled in the art in the light of the following explanation of the accompanying drawings illustrating 15 what we now believe to be the preferred embodiment and mechanical expression of the invention from among other forms and constructions within the spirit and scope thereof.

20 An object of the invention is to provide a runner with an exceedingly strong, durable, and comparatively inexpensive nose composed of sections that can be readily assembled and secured and that will constitute 25 an effective brace and guard for the front end of the runner body.

The invention consists in certain novel features in construction and in combinations and arrangements as more fully and particu- 30 larly set forth and specified hereinafter.

Referring to the accompanying drawings:—

Figure 1, is a side elevation of a runner embodying our invention.

35 Fig. 2, is an elevation of the opposite side of the runner.

Fig. 3, is a sectional view on the line 3—3 Fig. 1.

40 Fig. 4, is a detail perspective view of the pressed steel blanks or sections.

In the drawings, we show the front portion of a runner wherein the wood portions thereof are formed by straight runner body 1 and a separate nose piece or filler 1^a, rising 45 from the front end of body 1, and having a flat bottom face resting on the flat or straight top edge 1' of said body. The bottom edge of the body 1, curves upwardly and forwardly at the front portion 2, and the front 50 or bottom edge of the nose piece 1^a, curves upwardly and forwardly in continuation thereof.

The body 1, is equipped with shoe 3, at its front end terminating at the curved edge 55 portion 2 of the body.

Our invention involves a peculiar metal casing or housing that completes the nose portion of the runner and renders the same exceedingly strong, rigid and durable, by approximately inclosing the nose piece 1^a 60 and the front end of the body 1 and by being continuous across the junction between said nose piece and body. This metal nose or housing is composed of two stiff rigid shells or sections, an upper longitudinal section, 65 and a lower longitudinal section, each section being pressed or struck up from sheet steel, although the invention is not so limited.

The upper longitudinal section curves upwardly and forwardly and faces the top edge 70 of the front portion of the body and the complete top edge of the nose piece and one vertical side face of the nose piece and a portion of the corresponding side face of the front end of the body, while the lower section 75 of said metal housing also curves upwardly and forwardly and faces the opposite vertical side face of the nose piece and portion of the body and the bottom edges of the nose piece and front end of the body. 80

The rear ends of these two metal housing sections are rigidly clamped and secured to the top and bottom edges of the front portion of the runner body by vertical bolt 12, passing through the body and sections at a 85 distance in rear of the nose piece 1^a.

The housing sections and the nose piece and body are also rigidly secured together by bolts 13, passing through the transverse walls of the sections and through the overlapping portions of the body and nose piece. 90

The upper section of the housing is formed with a longitudinal top wall or flange 6, that is continuous throughout the length of the top edge of the nose piece and across the junction between the rear end of said piece 95 and onto a substantial length of the top edge of the body 1. This wall tightly fits and conforms to the curvature of said edge of the nose piece and its rear portion approximately 100 conforms to the horizontal plane of the top edge of the body. Throughout the length of one edge said wall is formed with depending edge or narrow flange 6^a, slightly lapping one vertical side face of the nose piece and 105 of the front end of the body. At the opposite side edge of said wall 6, the section is formed throughout its length, with a longitudinal vertical wall 7, in the form of a deep or wide flange that snugly and approxi- 110

mately completely faces the other vertical side face of the nose piece and depends at the corresponding side face of the body and approximately covers the joint between said piece and body at said side face of the runner.

The lower section of the metal housing is formed with a longitudinal bottom wall or flange 8, corresponding to wall 6, of the upper section and extending from the front end of shoe 3, to the top edge of the nose piece 1^a, and fitting and conforming to the curvature of the bottom edge of the front end of the body 1, and the edge of the nose piece in continuation of said body edge. This wall 8 is continuous across the junction between the nose piece and body and extends throughout the length of said piece and is formed with an upturned edge or short flange 8^a, (corresponding to edge 6^a) engaging the same side faces of the nose piece and body that are engaged by vertical wall or wide flange 7, of the upper housing section.

25 The lower housing section is also formed with longitudinal vertical wall or wide flange 9, corresponding to vertical wall 7 and forming the other side or vertical wall of the housing and engaging the vertical side faces of the nose and body that are opposite those covered or partially covered by the vertical wall 7. The upper end of the nose piece is rounded and formed with a transverse opening, and the upper ends of the vertical walls 7, 9 of the metal housing are found with transverse apertures to register with the opening in said nose piece, and form the eye 4, of the runner nose.

Said opposite vertical walls of the housing are also preferably formed with bolt or rivet holes adjacent to said edge 4 to receive transverse bolts or rivets 10, extending through said walls and the nose piece and binding said vertical walls 7, 9, adjacent the side faces of the nose piece and the front ends of the housing sections against vertical play and separation.

50 The upper end of the top wall 6, is curved downwardly to provide the rounded or convexed portion 6^b fitting down on and conforming to the rounded upper end of the nose piece, and terminating in the transverse end edge 6^c.

55 The upper end of the wall 8, is curved upwardly and rearwardly to provide the rounded or convexed portion 8^b fitting and conforming to the said rounded end of the nose piece, and terminating in the transverse end edge 8^c.

60 The vertical walls 7, 9, preferably increase in vertical depth toward the upper or front end of the housing and are notched and rounded at their upper ends to permit the edges 6^c and 8^c, to abut and the edges of the walls 9, 7, to abut the edges of the short

flanges or edge 6^a, 8^a, when the housing sections are secured together and to the wood members of the runner. These sections thus form a hollow metal nose or housing approximately completely inclosing the upper end of the nose piece.

It will be noted that each section of the metal housing is approximately L shape in cross section.

This metal housing renders the nose of the runner exceedingly strong, rigid and durable and so braces and protects the joint between the wood nose piece and runner body as well as the wood nose as to render the runner as an entirety of maximum strength and durability.

75 It is evident that various changes, modifications, and variations might be resorted to without departing from the spirit and scope of our invention and hence we do not 80 wish to limit ourselves to the exact disclosures hereof.

What we claim is:—

1. In a bob sled runner, a runner body, and a metal nose therefor comprising a 90 lower longitudinal section having a longitudinal bottom wall fitting the lower edge of the front portion of said body and forming the shoe therefor and having a longitudinal vertical side wall fitting one vertical 95 side face of said body, and an upper longitudinal section having a longitudinal vertical side wall fitting the other vertical side face of said body and having a longitudinal top wall engaging the top edge of said body, 100 the longitudinal edges of said vertical walls at the front ends of the sections abutting against the inner faces of said bottom and top walls to form the eye of the nose, and securing bolts passing through said body 105 and rigidly clamping said bottom and top walls thereto and the front ends of said sections together.

2. A bob sled runner comprising a runner body, a nose piece thereon, a metal nose 110 composed of a pair of longitudinal sections, each section being approximately L-shape in cross section, and a longitudinal series of vertical bolts passing upwardly through one of said sections, the runner body, the nose 115 piece and the other section and rigidly uniting the nose to the body and clamping said sections against the top and bottom edges of the body and nose piece, one section fitting one vertical side face of the body and 120 the other section fitting the opposite vertical side faces and piece of the body.

3. A bob sled runner comprising a runner body, and a metal nose therefor longitudinally fitting the opposite vertical side faces 125 of the body and the top and bottom edges thereof and projecting upwardly and forwardly therefrom and rigidly secured thereto and forming a front eye, said nose composed of upper and lower longitudinal sec- 130

tions rigidly clamped together, one section forming one side wall and a portion of the edge wall of said eye and the other section forming the other side wall and the remainder of the edge wall of said eye.

4. A bob sled runner comprising a runner body and its nose piece, and a metal nose therefor fitting the opposite side faces and top and bottom edges of the front end portion of the body and its nose piece and securing means passing through said body and nose piece and rigidly holding the nose to the top and bottom edges thereof, said nose being composed of upper and lower

longitudinal sections, each approximately 15 L-shape in cross section, the upper section forming the top wall and one side wall of the nose, the lower section forming the other side wall and the bottom wall of the nose, said top and bottom walls terminating in 20 approximately abutting transverse edges at the front end of the nose, the edges of said side walls at the front end of the nose abutting the inner faces of said top and bottom walls.

DAVID PLATTNER.
RODNEY H. YALE.
